UNITED STATES PATENT OFFICE.

GEORGE HAMILTON AMES, OF BROOKLYN, NEW YORK.

BARREL CLOSURE.

Application filed January 29, 1924. Serial No. 639,922.

My invention relates to barrel closures, my more particular purpose being to produce a barrel closure admitting of cheap construction, simple in operation and efficient in action, and suitable for use with oil and other liquids having great penetrative power.

More particularly stated I seek to produce a device of this character, suitable for use upon barrels used in shipping oil over long distances, and in which the danger of leakage is reduced to a minimum.

Reference is made to the accompanying drawing forming a part of this specification, and in which like reference characters indicate like parts throughout the several parts.

Figure 1 is a substantially central section through one form of my improved barrel closure, various movable parts of the device appearing in the positions they occupy before the closure is sealed.

Figure 2 is a side elevation of a steel barrel with my improved closure so applied thereto as to occupy a position substantially midway between the heads of the barrel.

Figure 3 is an end elevation of a steel barrel, and shows my device as applied to the head thereof.

Figure 4 is a side view, partly an elevation and partly a section, showing another form of my improved closure.

Figure 5 is a fragmentary elevation of the mechanism shown in Figure 1, and shows the same as sealed.

A steel barrel appears at 6, and carries a pair of annular supporting rims 7, these parts being of the usual or any desired construction.

The barrel is provided with a massive portion 8, serving as a base for the closure, and through this base extends a bung hole 9.

The base 8 is provided with a wall 10, integral with it and provided externally with threads 11. These threads may be of any suitable size, but are preferably about sixteen to the inch. The base is further provided with another annular wall 12, encircled by the wall 10 and concentric with the same. This wall 12 is also concentric with the bung hole 9.

Between the wall 10 and 12 is a channel 13 of annular form. Resting in the bottom of this channel is a gasket 14 made of cork or other resilient material and having the form of a flat ring. Resting upon this

gasket is a ring 15 made of soft-metal preferably Ames's alloy, or which may be a single pure metal, such as lead or aluminum.

A revolvable cap is shown at 16, and has integral with it a peripheral flange 17 of annular form, this flange being provided internally with threads 18, mating the threads 11 of the wall 10.

The cap 16 carries an angular head 19, to be engaged by a wrench and thus used for turning the cap. The cap carries a pair of annular cutting edges 20 and 21, the edge 21 being encircled by the edge 20 and concentric thereto. Between these edges 20 and 21 is a channel 23, and mounted within this channel is a gasket 24 made of cork or other resilient material.

When the cap 16 is turned relatively to the base 8 and in the proper direction, the cutting edges 20 and 21 are forced against the ring 15 and thus caused to cut into the same slightly, as indicated in Figure 5. The cork rings 14 and 24 are thus compressed, as indicated in Figure 5, and the cutting edges 20 and 21 are forced into the ring 15.

Thus is formed a very effective seal, through which oil, however penetrating and limpid, is unable to pass.

If the closure mechanism is used more than once, each time the cap is screwed in position as above described the cutting edges 20 and 21 cut a little more deeply than before, and as a result the cork gaskets 14 and 24 are each compressed to a little greater extent than before. Thus the seal as a whole is progressive in its action, in that the movable parts occupy slightly different positions relatively to the stationary parts as the closure is sealed from time to time.

A very important feature of the device is the action of the cutting edges 20 and 21, as they force their way to a greater or lesser extent into the ring 15. They cut a little deeper each time they are used successively.

In the form shown in Figure 4 the base appears at 8, and has nearly the same construction as the one above described. In this instance, however, the annular channel 13 is occupied by a filling 25 by soft metal, such as Ames's alloy, aluminum or lead. The filling should adhere to the base, so as to be practically integral therewith. For this purpose the filling may be cast or moulded in the channel, and a flux may be used for the purpose of facilitating the in-

tegrality of its union with the base. However, if desired the filling may be made to adhere to the walls of the channel by any expedient already known in this art, such as soldering, sweating or casting, with or without a fluxing agent. It is an easy matter to thus render the filling 25 practically integral with the base 13, in such manner as to prevent oil or other liquid escaping by 10 passing underneath the filling according to Figure 4.

In the form shown in Figure 4 the cap 26 is provided with a single cutting edge 27 integral with it and having an annular 15 form. This cutting edge is so located, proportioned and arranged as to descend upon the middle of the filling 25 whenever the cap is screwed down. Each time the cap is thus screwed down the cutting edge 27 20 cuts into the filling, and if the cap is repeatedly removed and replaced, or in other words if the barrel bung is repeatedly opened and closed, each successive closing causes the cutting edge 27 to penetrate into the 25 filling 25 a little more deeply than before.

Whenever the filling is worn out, or cut so deeply so as to be inefficient, it can be recast either in the channel that it occupies or otherwise, or a new filling may be substituted for it.

Either form of the filling above described is suitable for use in shipping oil contained in barrels, in instances where the barrels are shipped over long distances and in which 35 they are subjected to climatic extremes in temperature.

The parts employed are few in number, easily manufactured and easily standardized. The device is well adapted for quantity production.

I do not limit myself to the particular mechanism shown, as variations may be made therein without departing from my invention, the scope of which is commensurate with my claims.

Having thus described my invention, what I claim as new and desire to secure by Letters Patent is as follows:

1. In a device of the character described 50 the combination of a containing vessel provided with a bung hole and with a threaded

portion encircling said bung hole, a cap provided with a threaded portion mating said first mentioned threaded portion so as to enable said cap to be screwed down relatively 55 to said containing vessel, said containing vessel being further provided with a channel, a gasket fitted into said channel, a filling of soft metal located within said channel and engaging said gasket, a pair of cutting 60 edges carried by said cap and separated by a channel, and a gasket of resilient material located within said last mentioned channel and thus carried by said cap.

2. In a device of the character described, 65 the combination of a containing vessel provided with a bung hole and with a threaded portion encircling said bung hole, a cap provided with a threaded portion mating said first mentioned threaded portion so as 70 to enable said cap to be screwed down relatively to said containing vessel, said containing vessel being further provided with a channel encircling said bung hole, a filling of soft metal located within said channel, 75 a pair of cutting edges of annular form carried by said cap and separated by a channel, and a filling of resilient material carried by said cap and located within said last mentioned channel.

3. In a device of the character described, 80 the combination of a containing vessel provided with a bung hole and with a threaded portion encircling said bung hole, said containing vessel being further provided with a channel encircling said bung hole, a filling of soft metal fitted into said channel and thus encircling said bung hole, a cap provided with a threaded portion mating said first mentioned threaded portion so as to 85 enable said cap to be screwed down relatively to said containing vessel, said cap being further provided with a pair of cutting edges of annular form separated by a channel, and an annular closure member carried by said cap and located within said last mentioned channel, in engagement with said filling of soft metal.

Signed at New York, in the county of New York and State of New York, this 28th 100 day of January, 1924.

GEORGE HAMILTON AMES.
